Primary Examiner — Jonathan J Han(74) *Attorney, Agent, or Firm* — Marshall A. Lerner;
Steven J. Kim; KLEINBERG & LERNER, LLP(57) **CLAIM**

The ornamental design for a shoe outsole as shown and described.

DESCRIPTION

FIG. 1 is a bottom plan detail view of a shoe outsole.

FIG. 2 is a left side view thereof;

FIG. 3 is a right side view thereof;

FIG. 4 is a rear view thereof;

FIG. 5 is a front view thereof; and,

FIG. 6 is a bottom plan view of the portion of the shoe outsole of FIG. 1 shown within a shoe environment.

The dashed lines represent environmental portions of the shoe outsole and environmental structure that form no part of the claimed design. The broken lines enclosing the shoe outsole portions in FIGS. 1 and 6 form no part of the claimed design.

1 Claim, 4 Drawing Sheets(56)
